UNITED STATES PATENT OFFICE.

DANA OSGOOD, OF HOPEDALE, MASSACHUSETTS, ASSIGNOR TO DRAPER COMPANY, OF HOPEDALE, MASSACHUSETTS, A CORPORATION OF MAINE.

WARP STOP-MOTION FOR LOOMS.

1,129,810.

Specification of Letters Patent. Patented Feb. 23, 1915.

Application filed February 15, 1913. Serial No. 748,557.

To all whom it may concern:

Be it known that I, DANA Osgood, of Hopedale, Worcester county, Massachusetts, have invented a new and Improved Warp 5 Stop-Motion for Looms, of which the following is a specification.

The improvements are illustrated in the accompanying drawings, which show a vertical cross-section of so much of a loom as is 10 necessary to enable the invention to be understood.

In the drawings, A, A, are thin sheet metal drop-bars or detectors, each having a longitudinal slot a; B, B, are two sheet metal lease rods, each having inturned separated beads b, b, underneath with a gap between them, so that each lease rod has a longitudinally extending groove or recess on its underside; C, C, are guide bars, one for each 15 bank of detectors, each guide bar extending through the slots a, of the detectors of one bank; D, and E, are the two sheds of warp threads divided into intersecting planes by the lease rods; and F, is an arrow indicating 20 the direction of feed of the warp threads in the loom. Each warp thread passes through the slot of one of the detectors, and normally supports that detector which is thus suspended. There are as many 25 detectors in both banks as there are warp threads in the loom. The detectors are suspended from the bottom sheds.

Each guide C, is directly beneath one of the lease rods B, so that the upper ends of 30 the detectors in one bank extend within the recess on the under side of the corresponding lease rod. Hence it is impossible for the detectors of one bank to come into contact with the warp threads from which the 35 other bank of detectors is suspended, thereby avoiding chafing of the threads of one shed by the detectors belonging to the other shed. The head of each detector is normally well below the under face of the top 40 of the lease rod above it, and the recess is wider than the detector, so that the detector is not in contact with the lease rod.

Each detector is free to move vertically 45 both up and down and laterally both ways, so that the detectors accommodate themselves to the threads and the strains thereon.

In case a warp thread breaks its detector drops, being guided by its guide bar C, and is suspended in its dropped abnormal

position by said guide bar. A detector in 55 its dropped or abnormal position effects the stoppage of the loom through any of the well-known coöperating devices which may be electrical or mechanical, for example, in accordance with the known teachings of the 60 art.

I claim:

1. A warp stop motion for looms comprising, in combination, sheet metal lease rods, each with a longitudinally extending recess 65 on its underside, said rods dividing the warp threads into intersecting planes; a guide below each lease rod; and a bank of slotted thin sheet metal drop-bars or detectors for each lease rod, the guide below 70 each rod extending through the slots of all the detectors of one bank, and each detector being suspended from a warp thread with its head located within the recess of a lease rod, but out of contact therewith. 75

2. A warp stop motion for looms, comprising, in combination, lease rods, each recessed on its under side; a bank of detectors for each lease rod, each detector being suspended from a warp thread beneath a lease 80 rod and with its head within the recess of the lease rod, but out of contact with the lease rod; and means for guiding the detectors.

3. A warp stop motion for looms comprising, in combination, leasing means to dispose the warp threads into intersecting planes, and a bank of detectors for each means, each detector being suspended vertically from a single thread under one of 90 the leasing means and out of contact with all of the leasing means. 85

4. A warp stop motion for looms comprising, in combination, means to dispose the warp threads into intersecting planes 95 consisting of a leasing instrumentality forming the upper half of each lease and two separated instrumentalities forming the lower half of each lease, and a bank of detectors for each plane of warp threads, each 100 detector being suspended vertically from a single thread under and out of contact with the leasing instrumentality forming the upper half of each lease, and between the two leasing instrumentalities forming the 105 lower half of each lease.

5. A warp stop motion for looms having, in combination, a rod dividing the warp-

threads into different planes, and drop-wires hung upon the warp-threads vertically in line with the rod, and having the said rod constructed with clearance above the 5 upper ends or heads of the drop-wires.

6. A warp stop motion for looms, comprising, in combination, lease rods, each recessed on its under side; a bank of detectors for each lease rod, each detector being suspended from a warp thread beneath a lease 10

rod, but out of contact with the lease rod; and means for guiding the detectors.

In witness whereof, I have hereunto signed my name in the presence of two subscribing witnesses.

DANA OSGOOD.
